UNITED STATES PATENT OFFICE.

OLE OLSEN, OF ST. LOUIS, MISSOURI.

STREET-CAR FENDER.

SPECIFICATION forming part of Letters Patent No. 705,783, dated July 29, 1902.

Application filed August 7, 1901. Serial No. 71,197. (No model.)

To all whom it may concern:

Be it known that I, OLE OLSEN, a citizen of the United States, and a resident of the city of St. Louis and State of Missouri, have invented 5 certain new and useful Improvements in Street-Car Fenders, of which the following is a specification.

My invention relates to street-car fenders.

It frequently happens with street-car fenders of the styles now in use that a person struck thereby is thrown forcibly against the solid portion of the car.

It is the principal object of the present invention to avoid serious injury to a person 15 who is struck by the fender.

Another principal object is to cheapen the construction of the fender as much as practicable.

My invention consists in the construction 20 and arrangement of parts hereinafter described and claimed.

In the accompanying drawings, which form part of this specification, and wherein like symbols refer to like parts wherever they occur, Figure 1 is a perspective view of the frame of my fender mounted on the end of a car. Fig. 2 is a detail view of the under side of the apron, and Fig. 3 is a cross-section of my device mounted on the car.

30 The body of my device comprises a skeleton frame 1 of oblong form, having arms 2 projecting rearwardly at each end. These arms are pivotally supported on hangers 3, provided therefor on the under side of the 35 car-body 4. For this purpose the arms 2 and hangers 3 are preferably perforated, and a rod 5 extends through them to constitute a pintle. This rod 5 is preferably made removable, so as to facilitate the dismounting 40 of the fender.

On the inside of the front and sides of the fender-frame is mounted a rod or jack-stay 6. A similar rod or jack-stay 7 is mounted upon the front end of the car-body. To these rods 45 or jack-stays respectively is laced an apron 8, of canvas or other suitable material, properly fitted thereto to cover the end of the car. As shown in Fig. 2, this apron has a heavy cord or rope 9 around its edge on the lower side 50 and is provided with eyelets or lacing-holes 10 around its margin. By this arrangement the canvas is to a large extent relieved of

wear, the danger of tearing is reduced, and a worn apron can be replaced with a new one with great facility.

55

Mounted upon the rear bar 11 of the fender-frame is a notched link or rack 12, which extends upwardly through a hole 13 in the car-body in position to have its notches co-operate with a detent 14, mounted on the car-body in convenient position to be actuated by the foot of the motorman. As shown in Fig. 1, this detent 14 consists of a spring mounted in front of the dashboard 15 and projecting through a hole 16, provided therefor in the dashboard; but obviously said detent may be located wherever it may be operated conveniently. In ordinary use the link is raised to elevate the front edge of the fender a considerable distance above the ground. When 70 the fender is to be applied, the motorman merely disengages the detent from the rack, whereupon the fender falls of its own weight. When it is desired, the link is raised to the full limit, whereby the fender-frame is tilted 75 into an almost vertical position. In order to permit the fender to assume this position, the hangers upon which it is pivotally mounted are located close to the front end of the car-body.

80

In order to prevent a person who has fallen onto the fender from rolling off, the fender is provided with raised sides or guards 16, as shown in Fig. 3.

What I claim is—

85

1. The combination with a car having a jack-stay on the end thereof, of a car-fender pivotally supported on the car-body, said fender comprising a frame, a jack-stay thereon, and an apron laced to said jack-stays, substantially as described.

90

2. A car-fender having a pivotally-supported frame, a jack-stay thereon, and an apron connected to said jack-stay, substantially as described.

95

3. A car-fender having a pivotally-supported skeleton frame, a jack-stay thereon, and a canvas apron connected to said jack-stay, substantially as described.

100

4. A car-fender comprising an apron having a rope secured to its edge on the under side, substantially as, and for the purpose set forth.

5. A car-fender comprising an apron hav-

ing a rope secured to its edge on the under side and having eyelets near said edge, substantially as, and for the purpose set forth.

6. The combination with a car having a 5 jack-stay on the end thereof, of a car-fender pivotally supported on the car-body, said fender comprising a frame, a jack-stay thereon and an apron having a rope secured to its

edge on the under side, said apron being laced to said jack-stays, substantially as described.

OLE OLSEN.
